LEROY TROWBRIDGE
INVENTOR

BY *Victor J. Evans*

ATTORNEY

UNITED STATES PATENT OFFICE.

LEROY TROWBRIDGE, OF SPRINGFIELD, SOUTH DAKOTA.

SEESAW.

Application filed March 31, 1923. Serial No. 629,044.

To all whom it may concern:

Be it known that I, LEROY TROWBRIDGE, a citizen of the United States, residing at Springfield, in the county of Bon Homme 5 and State of South Dakota, have invented new and useful Improvements in Seesaws, of which the following is a specification.

This invention relates to amusement devices and more particularly to a seesaw and 10 an object of the invention is to provide a seesaw which permits pivotal movement of the seat portions of the seesaw with relation to the pivotal movement of the major portion or body of the seesaw permitting the 15 seat portions to remain in horizontal position at all times and eliminating the liability of the occupants of the seesaw from sliding towards the center of the seesaw during its operation.

20 Another object of the invention is to provide hand grips in the improved seesaw structure which are connected by suitable leverage structures to the seat portions so as to permit the occupants to move their body 25 in unison with the movement of the seat portion and body portion and maintain themselves in a comfortable position.

Other objects of the invention will appear 30 in the following detailed description and in the accompanying drawing wherein:

Fig. 1 is a side elevation of the improved seesaw.

Fig. 2 is a top plan of the seesaw,

35 Fig. 3 is a vertical section taken on the line 3—3 of Fig. 2.

Fig. 4 is a vertical section taken on the line 4—4 of Fig. 2.

Referring more particularly to the drawing the improved seesaw comprises the 40 standard 1 which in turn comprises side members 2 which are driven into the ground as clearly shown in Fig. 1 of the drawing and which are connected by transverse braces 3 so as to provide a rigid, secure 45 structure. The board or body 4 of the seesaw rests upon or is suitably attached to a pivot pin 5 which is carried by the upper ends of the side members 2 to permit rocking of the body or board 4. A centrally located 50 arm or member 6 is attached to the cross

braces 3 and extends through a slot 7 formed in the board 4 and it serves to limit longitudinal movement of the board 4 relative to the standard structure 1 during the rocking or pivotal movement of the board. A 55 bar 8 is pivotally connected to the upper forked end 9 of the member 6 and it extends parallel with the board 4. Levers 10 are pivotally connected to the ends of the bar 8 and extend downwardly through the opening 11 in the board 4 adjacent each end of the board. The levers 10 are pivotally connected to the board by means of suitable pivot bolts or pins 12. The lower ends of the levers 10 are in turn pivotally connected 60 to levers 13 which are in turn pivotally connected as shown at 14 to the under surfaces of the seat portions 15 of the seesaw. The seat portions 15 are hingedly connected by means of hinges 16 to the ends of the board 4 so as to permit seat portions to remain in substantially horizontal position during the 65 rocking or teetering of the board 4. Hand grips 17 are carried by bolts 18 which pivotally connect the upper ends of the levers 10 70 to the bar 8.

By particular reference to Fig. 1 of the drawing it will be noted that the hand grips 17 and the seat portions 15 are arranged so that when the occupant is seated upon the 80 seat portion with his hands gripping the hand grips 17 he can by slightly swinging his body with the movement of the board 4 and by applying slight pressure to the hand grips rock the board 4 and at the same 85 time maintain himself in substantially erect and comfortable position. Through the medium of the levers 10 and 13 the seat portions 15 will move in unison with the board 4 and will substantially maintain their 90 horizontal position.

It is, of course, to be understood that the invention may be constructed in various other manners and the parts associated in different relations and, therefore, I do not 95 desire to be limited in any manner except as set forth in the claim hereunto appended.

Having thus described my invention what I claim is:

In a seesaw, a standard, a board, a sup- 100

porting pin rockably supporting said board from said standard, said board provided with a centrally located slot, a member rising from said standard and extending through said slot for limiting longitudinal movement of the board relative to the standard, seat portions pivotally connected to

the ends of said board, and pivotally connected levers connecting said seat portions to the ends of the board independently of the pivotal connection between the seat portions and board. ¹⁰

In testimony whereof I affix my signature.

LEROY TROWBRIDGE.
